UNITED STATES PATENT OFFICE

HENRY J. HEINZ, OF PITTSBURG, PENNSYLVANIA.

DESIGN FOR A PICKLE-BOTTLE.

SPECIFICATION forming part of Design No. 12,844, dated April 4, 1882.

Application filed January 27, 1882. Term of patent 14 years.

To all whom it may concern:

Be it known that I, HENRY J. HEINZ, of Pittsburgh, in the county of Allegheny and State of Pennsylvania, have invented a new and useful Improvement in Design for Pickle-Bottles; and I do hereby declare the following to be a full, clear, and exact description thereof, reference being had to the accompanying drawings, forming a part of this specification, in which—

Figure 1 is a perspective view of my new pickle-bottle. Fig. 2 is a side view of the same slightly modified, and Fig. 3 is a cross-section.

Like letters of reference indicate like parts in each.

My improved design consists of a bottle the body *a* of which is a parallelogram in cross-section. It has a squat rounded shoulder, *b*, and a tubular neck, *c*, terminating at a ring or

lip, *d*, to which a paper or foil cap, *f*, may be applied. I prefer to have a ring, *e*, at the junction of the neck and shoulder; but this may be omitted, as shown by Fig. 2. This bottle has a handsome appearance, and one which is very appropriate to the use for which it is designed. This bottle is designed for use with all kinds of pickles, horse-raddish, and other condiments.

What I claim as my invention, and desire to secure by Letters Patent, is—

The design for bottle, substantially as described and shown.

In testimony whereof I have hereunto set my hand this 13th day of January, A. D. 1882.

HENRY J. HEINZ.
